UNITED STATES PATENT OFFICE.

TULLY LA TESSA, OF CHICAGO, ILLINOIS, ASSIGNOR TO BLOCK PORTELIER COMPANY, OF CHICAGO, ILLINOIS, A CORPORATION OF ILLINOIS.

DESIGN FOR A COLUMN FOR LAMPS.

Application filed April 19, 1926. Serial No. 17,338. Term of patent 3½ years.

To all whom it may concern:

Be it known that I, TULLY LA TESSA, a citizen of the United States, residing at Chicago, in the county of Cook and State of Illinois, have invented a new, original, and ornamental Design for a Column for Lamps, of which the following is a specification, reference being had to the accompanying drawing, which forms a part thereof.

Figure 1 is a side elevational view of a

column for a lamp embodying my design, the balance of the ornamentation within the dotted outline being a repetition of the fragment shown; and

Figure 2 is a top plan view of the same.

I claim:

The ornamental design for a column for lamps, substantially as shown.

TULLY LA TESSA.
